UNITED STATES PATENT OFFICE.

HERBERT E. KEELER, OF NEW YORK, N. Y.

STAY-ROLLER FOR CAR-DOORS.

No. 912,382.

Specification of Letters Patent.

Patented Feb. 16, 1909.

Application filed September 19, 1908. Serial No. 453,723.

To all whom it may concern:

Be it known that I, HERBERT E. KEELER, a citizen of the United States, and resident of New York city, county of Kings, and 5 State of New York, have made a certain new and useful Invention Relating to Stay-Rollers for Car-Doors, &c., of which the following is a specification, taken in connection with the accompanying drawing, forming 10 a part of the same.

This invention relates to stay rollers adapted for use with sliding doors for railway cars and other purposes and relates especially to stay rollers comprising a curved 15 or reflexed inclosing attaching spring having integral attaching means adjacent one end and having integral bearing members adjacent its free end to pivotally support the roll which is substantially inclosed and protected 20 by this spring.

In the accompanying drawing showing in a somewhat diagrammatic manner illustrative embodiments of this invention in which the same reference numeral refers to similar 25 parts in the several figures, Figure 1 is a horizontal sectional view showing one form of the device applied to a door. Fig. 2 is a transverse sectional view of the same taken substantially along the lines 2—2 of Fig. 1. 30 Figs. 3, 4, 5 and 6 are corresponding horizontal sectional views showing other forms of the device applied to doors or the like.

In the illustrative embodiment of this invention shown in Figs. 1 and 2 the roll 1 of hard wood, metal or other suitable material 35 preferably having a slightly curved tread as indicated in Fig. 2, may be mounted in any desired way in the roll brackets 3 as by providing a suitable bearing sleeve 22, which 40 may project slightly beyond the ends of the roll and be supported by the pin or pivot 2 which may be riveted or otherwise secured to the brackets 3. These brackets may, if desired, be formed integral with the supporting 45 spring 4 of resilient sheet brass, phosphor bronze or other suitable material, these brackets or integral bearing members being preferably formed adjacent the free end of the spring by bending up suitable projections or lateral extensions of the spring. 50 Suitable attaching means may be used to secure the other end of the spring 4 to the door jamb or other support adjacent the door and such attaching means may, if desired, be in the form of integral ears 5 adjacent the end of the spring and formed

with holes 6, through which the attaching screws are adapted to engage. The spring may be formed with an outer inclosing convolution comprising the curve 10 to coöperate with the door jamb and portions 11, 12 and 13, the curve 14 thus being located sufficiently near the door to properly protect the roll and prevent material being drawn thereunder. If desired, also, the spring may be 60 reflexed to form another inner convolution substantially parallel to the outer inclosing convolution or part of the same; such convolution being indicated in Fig. 1 as comprising portions 15, 16 and 17. A still 70 further convolution comprising the parts 18, 19 may, if desired, be formed within the portion 17 and substantially parallel thereto and have the roll brackets 3 and the integral transverse aliners 20 formed thereon. These 75 aliners as indicated in Fig. 2, may extend adjacent to the lateral edges of the spring portions 17, 19, so as to prevent their getting out of alinement and be formed with the adjustable stop ears 21 adapted to coöperate 80 with the portion 11 of the spring in case the roll forces the same outward to an excessive extent so as to increase the spring resistance and prevent the door becoming unduly displaced in a lateral direction. It is of course 85 understood, that the stop ears may be readily adjusted by bending the same so as to regulate the extent of movement of the roll required to bring them into operative engagement with the outer portion 11 of the attaching spring. 90

The illustrative form of device shown in Fig. 3 embodies a similar roll 1 mounted on the pin 2 in the roll brackets 3 which may be formed integral with the inclosing attaching spring which may have integral attaching ears 5 at its other end by which the device may be secured by suitable means such as the attaching screws to the door jamb 8. The curved inclosing portion of 100 the spring 31, 32 and 33, serves to substantially inclose and protect the roll and the downward extending reflexed portion of the spring 23, 24 and 25, gives additional resiliency and may be joined by the curved 105 portion 30 with the free end of the spring. Suitable adjustable stop and alining means may be provided if desired, by forming suitable elongated slots 35, 36, in the reflexed portion of the spring with which the stop 110 member or screw 34 engages, thus holding the parts against lateral displacement by

engagement with the sides of the slots, as well as limiting the extent to which the spring yields and increasing the intensity of action of the spring as soon as the portion 25 engages the head of the screw.

In the illustrative form of device shown in Fig. 4, a similar roll 1 is mounted on the pin 2 in suitable bearing members such as the integral roll brackets 3 on the free end 10 41 of the attaching and inclosing spring. The portion 39, 40, 41 of the spring may serve as indicated, to substantially inclose and protect the roll when in operation and suitable attaching means such as the integral ears 5 may be provided at the other end of the spring to attach the same to the door jamb or other adjacent support in connection with suitable members such as the screws 7. This attached end 37 of the spring 15 is indicated as having a curved connection with the inclosing curved convolution of the spring around the roll. A similar device is indicated in Fig. 5, the curved inclosing convolution of the spring 48, 49, 50, 20 being indicated as provided with the integral roll brackets 3 supporting the pin 2 and roll 1 for coöperation with the door or similar member. The attaching ears 5 are joined in this instance with the inclosing convolutions by the reflexed portions 42, 43, 25 44, 45 and 46 of the spring, thus giving additional resiliency thereto. In Fig. 6 the somewhat similar inclosing convolution 54, 30 55, 56, is shown adjacent the free end of the spring, supporting the roll 1, a reflexed portion 51, 52, 53, being arranged for compact mounting adjacent the jamb of the door, the convolution 53 lying within a suitable recess 58 in the jamb itself to further economize space and limit the projection of the 35 40 stay roller beyond the jamb.

Having described this invention in connection with a number of illustrative embodiments and proportions to the details of which disclosure the invention is not of course to be limited, what is claimed as new and what is desired to be secured by Letters Patent is set forth in the appended claims.

1. In stay rollers, a roll, a bearing sleeve

in said roll, a pivot pin extending through 50 said roll and sleeve, a curved reflexed inclosing attaching spring having integral attaching means adjacent one end and integral bearing members adjacent its free end to support said pin, said spring comprising 55 an outer inclosing convolution and reflexed inner substantially parallel convolutions, transverse aliners having adjustable stop ears attached to said spring to maintain the substantial alinement of the convolutions 60 thereof and to coöperate with said spring to limit the resiliency thereof.

2. In stay rollers, a roll, a pin, a curved inclosing attaching spring having attaching means adjacent one end and integral bearing members adjacent its free end to support 65 said pin and adjustable stop and alining means for said spring.

3. In stay rollers, a roll, a reflexed inclosing attaching spring substantially inclosing 70 and protecting said roll and having substantially parallel inner and outer convolutions and integral bearing members adjacent its free end to pivotally support said roll and attaching means adjacent the other end of 75 said spring.

4. In stay rollers, a roll, a curved protecting attaching spring protecting said roll and having integral bearing members adjacent its free end to pivotally support said 80 roll and attaching means adjacent the other end of said spring.

5. In stay rollers, rotary bearing means and a curved protecting attaching spring protecting said bearing means and having 85 bearing members adjacent its free end to support said bearing means and attaching means adjacent the other end of said spring.

6. In stay rollers, a roll and a curved inclosing attaching spring having integral attaching means adjacent one end and integral bearing members adjacent its free end to pivotally support said roll.

HERBERT E. KEELER.
